UNITED STATES PATENT OFFICE.

CHARLES H. MCKENNA, OF PROVIDENCE, RHODE ISLAND.

PORTABLE SAND AND GRAVEL DRIER.

1,189,597.

Specification of Letters Patent.

Patented July 4, 1916.

Application filed August 16, 1915. Serial No. 45,781.

To all whom it may concern:

Be it known that I, CHARLES H. MCKENNA, a citizen of the United States, residing at Providence, in the county of Providence and State of Rhode Island, have invented certain new and useful Improvements in Portable Sand and Gravel Driers; and I do declare the following to be a full, clear, and exact description of the invention, such as will enable others skilled in the art to which it appertains to make and use the same.

This invention relates broadly to driers for sand, gravel and similar materials, and more particularly to that type which is both knockdown and portable, and has for its object to provide a cheaply constructed device of this character which may be operated with a minimum amount of fuel.

Another object of my invention is to provide a drier composed of a plurality of heaters so constructed as to give a great amount of radiating surface.

Still another object is to provide novel means for holding the sand or other material to be dried in position on the heaters.

With these and other objects in view, the invention consists of certain novel features of construction, combination and arrangement of parts which will be hereinafter more particularly described and claimed.

In the accompanying drawing: Figure 1 represents a drier formed of a plurality of heaters constructed in accordance with my invention; Fig. 2 is an end view of one of these heaters; Fig. 3 is a central vertical longitudinal section taken on the line 3—3 of Fig. 4; Fig. 4 is a vertical transverse section taken on the line 4—4 of Fig. 3.

In the embodiment illustrated wherein similar reference characters designate like parts throughout the several views, 1 indicates broadly my improved drier composed of a plurality of horizontally aligned heaters 2, arranged in a parallel row. These heaters 2 are preferably formed of horizontally extending cylindrical sheet metal pipes 3 in which fire is designed to be built or placed. At one end of each heating chamber 3 is formed a vertically extending outlet pipe 4 preferably formed of a pipe similar in diameter and construction to the pipe 3. By referring to Fig. 3, it will be readily evident that this construction provides a heater

of right-angular formation, the fire chamber of which is considerably longer than the out-

let pipe. The inlet end of each of these heaters is provided with a substantially square vertically extending plate 5 which has an opening 6 formed therethrough of a diameter similar to the outer diameter of said pipe 3, said opening being disposed nearer to the bottom of said plate than the top and is designed to receive the end of the pipe 3 and form a support therefor for spacing said pipe above the ground. Guides 7 are formed in the outer face of each plate 5 and are designed to slidably receive a suitable door 8. The plates 5 as clearly shown in Fig. 1, are designed in overlapping engagement with each other to hold the sand or other material to be dried, in place on the heaters. This arrangement allows the total length of the pipes to be utilized, thus saving a large amount of heat which would otherwise be lost.

The outlet pipe 4 of my improved heater has a damper 9 arranged in its outer end for controlling the draft through the heating chamber. This damper in conjunction with the sliding door 8 assists materially in reducing the amount of fuel consumed and allows the drier to be operated at a minimum cost. Secured to the outer side of each of these outlet pipes 4 is a downturned hook 10 designed to receive therein a vertical transversely extending sheet metal plate 11 which is adapted to retain the material to be dried at the outlet end of the heaters in a manner similar to the plates 5. Adjacent the outlet end of each of the pipes 3 and on their lower sides is secured a foot 12 which is adapted to raise this end pipe an amount equal to that which the front end or inlet end is elevated.

In the operation of my improved drier the heaters are first placed side by side on the ground as shown in Fig. 1 with the flanges 5 in overlapping engagement and the plate 11 is then placed in position. When the heaters are thus placed in parallel arrangement on the bed of material to be dried, other material of a similar nature is then heaped on the top of the driers and the several heating chambers are then ready to receive the fire therein. When the material is sufficiently heated, the heaters are disassembled and removed to a new location where they are again set up and recharged.

From the foregoing description of the operation and advantages of my improved drier, it is evident that I have produced a

device which will readily accomplish the purposes for which it is designed.

While I have particularly described the elements best adapted to perform the functions set forth, it is obvious that various changes in form, proportion, and in the minor details of construction may be resorted to within the scope of the appended claims without departing from or sacrificing any of the principles of this invention.

Having thus described my invention, what I claim as new is:—

1. A knock-down portable drier comprising a plurality of heaters, means at one end 15 of the heaters to retain the materials to be dried thereon, a hook member at the opposite end of each of said heaters, and a removable transversely extending vertical plate adapted to be held in position by said 20 hooks.

2. In a knock-down portable drier, a plurality of heaters, an upright plate secured to one end of each of the heaters, a hook at the opposite end of each of said heaters, and a removable transversely extending vertical plate adapted to be held in position by said 25 hooks.

3. In a knock-down portable drier, a plurality of heaters each comprising a horizontally extending cylindrical fire chamber having an outlet pipe formed integrally with one end thereof and extending vertically therefrom, an upright plate secured to one end of each of the heaters, a hook secured to each of said outlet pipes, and a removable transversely extending vertical plate adapted to be held in operative position by said hooks.

4. In a knock-down portable drier, a plurality of heaters each comprising a horizontally extending cylindrical fire chamber having an outlet pipe formed integrally with one end thereof and extending vertically therefrom, a damper in the outer end 45 of each of said outlet pipes, and an upright plate secured to the inlet end of each of said heaters, a door for closing said end, a hook secured to each of said outlet pipes, a foot secured under the outlet end of each of said 50 fire chambers, and a removable transversely

extending vertical plate adapted to be held in operative position by said hooks.

5. In a knock-down portable drier, a plurality of heaters each comprising a horizontally extending cylindrical fire chamber, an upright plate secured to one end of each of the heaters, said plates being adapted for overlapping engagement, a hook at the opposite end of each of said heaters, and a removable transversely extending plate adapted to be held in operative position by said 55 hooks.

6. In a knock-down portable drier, a plurality of heaters arranged in parallel relation, an upright plate secured to one end of each of said heaters, said plates being arranged contiguously, a removable plate extending transversely of the heaters at the opposite end, said plates being adapted to retain the sand on the heaters, and means 60 for retaining said removable plate in position.

7. In a knock-down portable drier, a plurality of heaters arranged in parallel relation, an upright plate secured to one end of each of said heaters, said plates being overlappingly engaged for retaining the sand on said heaters, a removable vertical plate extending transversely of the heaters at the opposite end, and means for retaining said 70 removable plate in position.

8. An article of manufacture comprising a horizontally extending fire chamber, an upright outlet pipe extending from one end thereof, sand retaining plate secured to the free end of said horizontal chamber and extending thereabove, said plate also extending below the same to form a support, an additional support at the opposite end of the chamber, securing means on said outlet pipe, 85 and an additional sand retaining plate held by said means.

In testimony whereof I have hereunto set my hand in presence of two subscribing witnesses.

CHARLES H. MCKENNA.
